APPARATUS FOR HANDLING BARRELS AND LIKE ARTICLES

Karl F. Snow, Brecksville, Ohio, assignor to The
C. O. Bartlett & Snow Company, Cleveland,
Ohio, a corporation of Ohio

Application December 10, 1931, Serial No. 580,126

3 Claims. (Cl. 214—91)

This invention relates to an apparatus for handling barrels or like articles, and while this invention will be described as relating to the drying and handling of barrels which have been freshly coated or painted, it will be understood that this invention may be applied to the handling and treating of articles other than barrels, and the treating operation is not restricted to the drying of the freshly coated articles.

5 Numerous difficulties are encountered in the handling and drying of freshly coated barrels and like articles, some of which may be briefly summarized as follows: When the barrel or like article is in its freshly coated state, extreme care must be exercised so that the surface of the article is not permitted to come in contact with any objects which would mar such freshly coated surface. The most expedient manner in which such freshly coated barrels can be handled is to support the same on their chime rings until the body of the barrel has dried sufficiently to permit handling in the ordinary fashion. The drying of the freshly coated barrels is efficiently accomplished by conveying the same through a drying chamber which consists simply of a closed oven to which is supplied a draft of heated air so that the coating on the barrels is dried much more quickly than this result could be accomplished by having the barrels exposed to ordinary atmospheric conditions. For certain particular types of coating it has been found that in order to have the barrels dry by the time they have passed through the drying oven, it is necessary that such barrels remain in the oven for a considerable length of time. The time interval in which the barrels remain in the oven is controlled by two factors: First, the length of the path in the oven which such barrels follow, and, second, the speed at which the barrels are moved. If a considerable number of barrels are to be dried in a relatively short time, that is, if production is to go forward at a desirable rate, it becomes necessary to have an oven of considerable length unless some provision is made to provide a circuitous path for the barrels through the oven.

40

45

It has been found by actual experience that even though the barrels are heated for a considerable time, they remain tacky after being discharged from the oven, probably due to the fact that the heat maintains the coating of such articles in a soft state after the same has been dried. It is among the objects of my invention to provide an apparatus for handling and drying barrels and like articles, which shall have all

50

55

of the above mentioned desirable characteristics,

and which shall be able to accomplish the above said desirable acts. Other objects and advantages of my invention will appear as the description proceeds.

To the accomplishment of the foregoing and related ends, said invention, then consists of the means hereinafter fully described and particularly pointed out in the claims, the annexed drawings and the following description setting forth in detail certain mechanisms embodying the invention, such disclosed means constituting, however, but one of various mechanical forms in which the principle of the invention may be used.

In said annexed drawings:—

Fig. 1 is a plan view of one form of apparatus embodying the principles of my invention. Fig. 2 is an elevational view of the apparatus illustrated in Fig. 1. Fig. 3 is an elevational view of a portion of the apparatus illustrated in the previous figures. Fig. 4 is a transverse sectional view of the apparatus illustrated in Fig. 1 taken on a plane substantially indicated by the line 4—4. Fig. 5 is a transverse sectional view similar to Fig. 4 showing an alternative form of construction.

Referring more specifically to the drawings and more specifically to Figs. 1 and 2, the apparatus illustrated in these particular figures comprises a spraying or coating booth 1, which has positioned therein a coating or spraying machine 2 shown consisting of a pair of parallel rotatable shafts 3 which have flanged collars 4 mounted thereon for the purpose of rotatably supporting the barrels to be coated on their chime rings. The construction of this coating apparatus will be more clearly understood with reference to my co-pending application Ser. No. 427,627 filed Feb. 11, 1930 now Patent No. 1,871,430, so that a further description of this portion of the apparatus will not be gone into in this description. The spraying or coating booth may be provided with a vent stack 5 which is for the obvious purpose of discharging the noxious fumes from the booth. The coating apparatus 2 has associated therewith a pair of parallel skids 6 which carry the barrels on their chime rings from such coating apparatus to a feeding apparatus, the construction of which will be more clearly understood with reference to Figs. 1 and 3. The feeding apparatus consists of an oscillatable shaft 7 which has secured thereto arms 8 which, for each oscillation of the shaft 7, will feed a single barrel or like article from the skids 6 on to the apparatus next in line.

The apparatus unit which receives the freshly coated articles from the feeder arms 8 is an upender consisting of a pair of laterally spaced arms 9 which are secured at one end to an oscillatable shaft 10, the arms 9 provided with laterally directed projections 11, which have oppositely sloping upper faces so that the barrel is supported on its chime rings on such upender. A common form of frame generally indicated at 12, and preferably consisting of fabricated structural steel elements, is employed to support the hereinbefore described feeding and upending apparatus.

Positioned adjacent the upender, and extending therefrom for a considerable distance, is the oven or drying chamber 13, through which the freshly coated barrels are transported and consequently dried. As more clearly illustrated in Fig. 4, the drying oven 13 is substantially rectangular in form, consisting of lateral walls 14 provided with spaced transversely extending members 15 and 16, and of course the usual top and bottom members 17 which along with the side walls 14 form a closing chamber. Vent stacks 18 which are provided with suitable dampers 19 are mounted on the drying oven at spaced points, so that the egress of air from the drying oven may be accurately controlled and the efficiency of such oven increased. The barrels are conveyed through the drying oven in an upset condition, i. e., resting on their chime rings. The barrels are carried through the oven by means of a pair of endless chains 20 which run in channel shaped track ways 21. The track ways for the chains are supported by the transverse members 15 and 16. Suitable sprockets 22 and 23 positioned on transversely extending shafts located at opposite ends of the oven are provided for the endless chains. Longitudinally extending laterally spaced arms 24 project from the oven and have rollers 25 mounted therebetween to receive the barrels from the upender arms 9 and convey the same onto the endless chains 20.

From an inspection of Figs. 1 and 2 it will be noted that the closed portion of the drying oven extends only for part of the full length of the barrel conveyor chains 20, i. e., the barrels in being carried from one end of the drying apparatus to the other are moving in the closed chamber, but only part of the time. The end of the closed chamber terminating short of the end of the endless chain permits barrels to be conveyed by such chain for some time while exposed to the relatively cool atmosphere of the room, as compared with the heated air of the oven, and it is this exposure of the tacky barrels when initially discharged from the heating chamber which causes a hardening of the coated surface which makes such surface hard and dry so as not to be marred in subsequent handling. The barrels therefore, when they are discharged from the endless chains have their coated surfaces hard and dry, which would not result were the barrels to be discharged directly from the heating oven onto the receiving apparatus (not shown) for such barrels.

The actuation of the several handling units, associated with the receiving end of the drying oven is accomplished by means of a common form of motor 26 which drives a pinion 27 which meshes with a driving gear 28 secured to a shaft 29 which extends transversely of the drying oven, preferably intermediately of the upper and lower portions of the endless chains 20 and journaled in pairs supported on opposite sides of the oven. The shaft 29 has a pinion 30 secured to its oppo-

site end which meshes with a driving gear 31 secured to the end of a shaft 32 which extends transversely of the drying oven, and to which are secured the sprockets 22 about which the endless chains 20 are trained. The shaft 32 has a pinion 33 secured to one end which meshes with a pinion 34 which is secured to a transversely extending shaft 35. The shaft 35 has a crank arm 36 secured to one end thereof, which crank arm has pivotally secured thereto a lever arm 37, which at its opposite end is in turn pivotally secured to another crank arm 38 secured to one end of the shaft 10. The shaft 10 which is journaled in bearings mounted on the frame 12 has a beveled gear 39 secured thereto intermediately of its end which meshes with a beveled gear 40 secured to the shaft 7 carrying the feeder arms 8.

Rotation of the drive shaft of the motor causes a rotation of the crank arm 36 synchronously with the rotation of the sprockets 22 due to the fact that these elements are all intergeared. The rotation of the crank arm 36 will cause a reciprocation of the arm 37 which will cause an oscillation of the shaft 10 and consequently the feeder arms 8 and the upender arms 9. Synchronous operation of all of the feeding and handling units is therefore had so that the barrels are automatically fed to the drying oven so that they occupy proper relative positions on the endless chains 20 in their passage through the drying oven.

Referring specifically to Fig. 4, the air within the drying oven is heated by means of a plurality of steam conduits 41 arranged in banks along the sides of such oven. The barrels within the oven are therefore subjected to a heating atmosphere on all sides, so that the freshly coated surfaces thereof are equally and efficiently dried. The alternative form of construction illustrated in Fig. 5 is identical with the illustration in Fig. 4, with the sole exception that the hot air for drying the barrels, instead of being provided by having the air within the oven heated by means of banks of steam conduits such as 41, is supplied to the oven by means of a conduit 42 which is positioned under the bottom of the oven and beneath the barrels passing therethrough. The conduit 42 for the heating air, is provided with a valve 43 which is in the nature of a flat plate which has a plurality of apertures formed therein adapted to register with similar apertures formed in the upper covering of the conduits 42 when such valve member is in proper relative position on such conduit. By manipulation of the valve 43 which extends laterally from the oven the draft of hot air through the oven and over the barrels, may be accurately controlled to effectively accomplish the drying of the barrels therein.

In addition to the advantages of the hereinbefore described apparatus as enumerated at the outset of this description there are a number of other advantages which are believed to be so well known to those familiar with the art that a repetition thereof at this point is unnecessary. A further description of the apparatus comprising my invention is believed unnecessary for those familiar with the art, it being noted that in a number of instances the elements have been diagrammatically illustrated due to the fact that such parts are common forms of construction well known to those familiar with the art.

By employing the method of drying barrels which has been hereinbefore described, the barrels may be quickly and efficiently dried by an apparatus which occupies only a minimum amount of space and further, such barrels or like

articles when discharged from the apparatus will not be tacky, but will have a hard dry finish and capable of being handled without marring.

Other modes of applying the principle of my invention may be employed instead of the one explained, change being made as regards the mechanism herein disclosed, provided the means stated by any of the following claims or the equivalent of such stated means be employed.

10 I therefore particularly point out and distinctly claim as my invention:

1. In a mechanism for handling freshly painted barrels, and the like, in combination, an oscillating cradle adapted to support barrels in a horizontal position while receiving and discharging same, said cradle comprising an oscillating shaft and feeder arms fixedly mounted thereon in spaced relation such as to engage the chime rings of a barrel passed thereover; an up-ender so positioned as to receive barrels discharged from said cradle, said up-ender comprising an oscillating shaft mounted at right angles to said oscillating shaft first named and operating therewith through engaged bevel gears on said respective 25 shafts, and spaced up-ending arms fixedly mounted on said shaft secondly named, each of said up-ending arms carrying spaced projections engaging the chime rings of a barrel passed thereover; a conveyor adapted to receive and remove 30 barrels placed thereupon by said up-ender, said conveyor comprising a conveyor chain, and rollers so positioned as to contact the bottom chime rings of a barrel as it is being up-ended by said up-ending arms whose continued movement forces 35 the barrel over the said rollers onto said chain; and means oscillating said shaft last named

through an angle of about ninety degrees, whereby the said up-ending arms are lifted from horizontal to vertical and returned.

2. In a mechanism for handling freshly painted barrels and the like, in combination, an oscillating cradle having a shaft and rockers mounted thereon engaging the chime rings of a barrel in horizontal position with its axis parallel to said shaft; an up-ender having a shaft and arms so positioned as to receive a barrel discharged from said cradle as it oscillates and support same with its axis parallel to said arms, said arms being fixedly mounted at right angles to said up-ender shaft and carrying projections which engage the chime rings of a barrel resting thereon; intermeshing 15 gears mounted on said shafts whereby they oscillate synchronously; a conveyor positioned to receive barrels discharged from said up-ender; and power means oscillating one of said shafts.

3. In a mechanism for handling freshly painted barrels, and the like, in combination, an oscillating shaft and cradle arms mounted fixedly transversely thereof; a second oscillating shaft at right angles to said first shaft and operatively connected therewith; up-ending arms fixedly mounted by one end on said second shaft at right angles thereto, and so positioned that a barrel discharged from said cradle arms will be received thereby and held with its axis perpendicular to said second shaft; power means oscillating one of said shafts whereby said cradle arms and said up-ending arms move in synchronism; and a conveyor so positioned that it receives barrels as they are up-ended and discharged from said up-ending arms.

KARL F. SNOW.
